Primary Examiner — John Windmuller*Assistant Examiner* — John R Yeh(74) *Attorney, Agent, or Firm* — John Yun(57) **CLAIM**

The ornamental design for a window washer, as shown and described.

DESCRIPTION

FIG. 1 is a perspective view of a window washer;

FIG. 2 is a left side view thereof;

FIG. 3 is a right side thereof;

FIG. 4 is a front view thereof;

FIG. 5 is a rear view thereof;

FIG. 6 is a top view thereof; and,

FIG. 7 is a bottom view thereof.

The broken lines show portions of the window washer that form no part of the claimed design.
